Atwell.

UNITED STATES PATENT OFFICE.

ARTHUR G. ATWELL, OF NEWPORT, RHODE ISLAND.

AUTOMATIC STOP FOR SOUND-REPRODUCING MACHINES.

Application filed February 20, 1922. Serial No. 537,799.

To all whom it may concern:

Be it known that I, ARTHUR G. ATWELL, a citizen of the United States, and a resident of Newport, in the county of Newport and State of Rhode Island, have invented an Improvement in Automatic Stops for Sound-Reproducing Machines, of which the following description, in connection with the accompanying drawings, is a specification, like characters on the drawings representing like parts.

This invention relates to automatic stop devices for sound reproducing machines, and has for its object the provision of an efficient but simply constructed stop mechanism adapted to stop automatically the sound reproduction at some predetermined point.

The invention will be best understood by reference to the following description when taken in connection with the accompanying illustration of one specific embodiment thereof, while its scope will be more particularly pointed out in the appended claims.

In the drawings,—

Fig. 1 is a fragmentary top plan view of a portion of a common type of sound reproducing machine, the latter having one embodiment of the invention applied thereto in operative relation to the turn-table and tone arm;

Fig. 2 is a side elevation of the stop mechanism shown in Fig. 1 looking from the side opposite the tone arm;

Fig. 3 is a front elevation partly in section of the stop mechanism looking radially outward from the center of the turn-table; and

Fig. 4 is a plan view partly in section showing the different positions of the contact arm and brake member.

Referring to the drawings and to the illustrated embodiment of the invention therein illustrated, although capable of application to various types of sound reproducing machines, it is there shown as applied to a common type, of which there is merely shown a portion of the tone arm 7 with its attached sound box 9, a needle or other reproducer 11 and the cooperatively related turn-table 13, the latter having a down-turned edge flange or rim 15.

Herein the mechanism is adapted to automatically stop the reproduction of sound by stoppage of the motion of the turn-table,

and this takes place when the reproducer 11 has reached or approximated the inner end of terminus of the sound record groove presented by the record 14. This may be controlled in various ways, but herein the stop mechanism is controlled by effecting contact between a tone arm part, herein the side of the tone arm 7, and a contact piece 17 on the stop mechanism, the latter located within the path of the tone arm and adapted to be engaged when the latter has approached the terminus of the sound groove. This contact piece is operatively related to a suitable brake member by connections to be described, so that when engaged by the tone arm it moves to instantly apply the brake to the outer face of the turn-table flange 15.

Referring to the drawings, and particularly to Figs. 1 to 3 inclusive, the stop mechanism is supported upon a base plate 19 secured to the frame 21 of the reproducing machine, at one side of the tone arm and at the outside of the turn-table 13, as will be seen in Fig. 1. The plate 19 herein provides support for a brake carrying member 23, the latter consisting of a rod or shaft carrying at its end a brake member 25, which latter is located in operative relation to and at a suitable distance from the outer face of the turn-table flange 15. The brake member 25 may be of any suitable material, such, for example, as leather, so that when it is brought in contact with the flange it will create sufficient friction to bring the turn-table to rest. The support for the rod 23 is herein conveniently provided by up-turned portions 27 and 29 of the base plate 19, the rod being capable of both a longitudinal and rocking movement in these supports. To urge the brake member toward and against the turn-table flange, suitable means are provided, such as a coiled spring 31 interposed between the plate 27 and the inner face of the brake member, and the latter, as shown, may be adjustably mounted on the threaded end of the rod 23 so as to permit adjustment of its position relatively to the turn-table flange.

To provide operative connections between the brake rod 23 and the contact piece 17, the outer end of the brake rod itself is bent at substantially right angles to provide the up-turned arm 33, which arm therefore is capable of swinging about the axis of the

brake rod as the latter turns, and may also be moved bodily with the brake rod when the latter is drawn inwardly by the spring 31.

When the device is set in position for use, 5 the contact carrying arm is held in a fixed position, herein substantially upright, with the brake member retracted and the spring 31 compressed. When the reproducer approaches the terminus of the sound record 10 groove, the contact piece 17 is engaged by the tone arm and the contact carrying arm released from its set position, permitting the spring 31 to move the brake member against the turn-table flange and bring the latter to 15 rest.

To hold the contact carrying arm in set position, while permitting its release under a very slight pressure from the tone arm, I have provided a guiding device, which herein is in the form of a slot 35 formed, for convenience of manufacture, in the horizontally bent end 37 of the plate 29, the slot having a substantially straight portion (in which the arm 33 is shown seated in Fig. 4) and 20 an open-ended inclined portion which is inclined toward the turn-table. This arrangement is such that when the arm 33 is swung right-handedly, as viewed in Fig. 3, it moves through the inclined portion of the slot 25 gradually retracting the brake member from the turn-table flange until it seats itself in the straight portion of the slot, as shown in full lines in Fig. 4. In this position it is held set by the friction caused by the pressure of the brake applying spring, but, on 30 any slight pressure urging it in a counter-clockwise direction, it is released from the straight portion of the slot and moves quickly down the inclined portion thereof 35 until the brake seats against the turn-table flange. Preferably, though not necessarily, the brake member 25 is adjusted at such a 40 distance from the flange, and the strength of the brake applying spring is such, that the 45 brake contacts with the turn-table flange and is effective to stop the same when the carrying arm 33 has reached some position within the slot, such as the dotted line position shown in Fig. 4, so that it has a working 50 range within the limits of the slot 35 and is not required to leave the latter. The contact piece 17 being carried by the arm above 55 the slot, a relatively great leverage is secured for the action of the tone arm: so that a very slight pressure of the latter is sufficient to trip the brake.

The inclined inner wall of the slot 35 forms a guide which enforces a turning as well as an advancing movement of the arm 60 33 and the brake shaft 23 after the release of the latter, thereby providing an advancing movement which is substantially less than the total movement of the arm and shaft. This permits the employment of a 65 small clearance between the brake member

and the turn-table when the brake is set and minimizes the noise and shock which accompanies the impact of the member against the turn-table.

To the thrust of the spring in applying 70 the brake is also added the effect of the momentum of the parts carried by the contact carrying arm in swinging from the set position shown in full lines in Fig. 4 to the released position shown in dotted lines therein. 75

The described form of stop mechanism may be used in conjunction with an adjustment carried either by the tone arm or the stop device so as to vary the point or time when contact takes place. In the described 80 form of apparatus this is accomplished by constructing the contact piece 17 in the form of a cam which is secured to the tapered pin 39 by means of the thumb nut 41, the pin being seated in the bearing block 43 threaded or otherwise secured to the upper end of the arm 33. The cam and tapered pin may thus be turned about its tapered bearing seat and set to different positions of adjustment, the contour of the cam being such 85 that in these different positions the tone arm is caused to contact with it at different points in its path of travel. Coupled with the adjustable contact piece 17, there is preferably provided an indicator point 45 seated 90 in a recess on the top of the cam 17 so as to be relatively fixed thereon and secured to the cam by the thumb nut 41, together with a cooperating graduated segmental scale 47, the latter being herein formed of sheet metal 95 and having a supporting tongue 49 fixedly secured between the bearing block 43 and the arm 33 so that the arm, block and dial piece are secured together as one member. 100

The position at which the indicator must 105 be set on the scale for any particular record can be readily ascertained by placing the reproducer near the end of the sound groove and adjusting the contact arm to a position where the release of the arm 33 from the 110 straight portion of the slot 35 will take place under the resulting pressure of the tone arm. The position on the scale beneath the pointer 45 may then be marked upon the record for future reference. When a record 115 is placed upon the turn-table it is only necessary to move the pointer to the number on the scale corresponding to that appearing on the record to insure the automatic stoppage of the turntable when the end of the 120 sound groove has been reached.

Since the contact member is adjustably mounted on the swinging arm 33, the device may be differently adjusted for separate 125 records without turning the arm or otherwise disturbing its relation to the shouldered portion of the slot which releasably holds it in set position. Any slight shaping of the shoulder or arm relatively to each other which may be availed of to increase or de- 130

crease the delicacy of release is not therefore disturbed by the adjustment to different records.

While I have herein shown for the purpose of illustration one specific embodiment of the invention, it is to be understood that the same is not limited to the form or relative arrangement of parts or to mechanical details herein shown, but that various applications of the same may be made and extensive deviations had from the illustrated details without departing from the spirit of the invention.

Claims:

15. 1. An automatic stop mechanism having a turn-table brake, a brake applying member to which the brake is attached, the same comprising a rod capable of a turning movement and also a longitudinal brake-applying movement, a spring to move said member toward a brake-applying position, a contact carrying member comprising an upright, swinging arm secured to the brake applying member and movable with the same, means to releasably hold the arm set with the brake applying member retracted but permitting said arm to be released by pressure of the tone arm to cause a spring actuated brake-applying movement, said 20 means including a slotted guide presenting guiding walls inclined toward the turn-table, and an adjustable contact carried by said arm comprising a cam with an indicator and scale to indicate the position of 25 the cam.

20. 2. An automatic stop mechanism having a turn-table brake, a brake applying member to which the brake is attached capable of a turning movement and also a longitudinal brake-applying movement, a spring to move said member toward a brake applying position, a swinging contact carrying member secured to the brake applying member and movable with the same, means to releasably hold the contact carrying member set with the brake applying member retracted, but permitting said contact carrying member to be released under action of the tone arm to cause a spring actuating 25 brake-applying movement and a contact piece adjustably mounted on said contact carrying member.

25. 3. An automatic stop mechanism having a turn-table brake, a rod to which the same is secured, said rod having longitudinal movement and a turning movement, an arm secured to said rod, a tone arm contact carried by said arm and adjustably mounted thereon, and a guide to hold said arm and rod retracted but to permit the same to be released under pressure of the tone arm to cause a spring actuated brake-applying movement.

30. 4. An automatic stop mechanism having the turn-table brake 25, the brake member

23, the swinging arm 33 secured thereto, the guide 35 providing for both an advancing and a turning movement of the brake member when the arm 33 is released, the contact 17, and the spring 31.

70

5. An automatic stop mechanism for a sound reproducing machine having a turn-table brake, a sliding, brake-carrying rock shaft, a swinging contact arm carried thereby, a contact piece adjustably mounted thereon and a device for releasably holding the arm and shaft retracted.

75

6. An automatic stop mechanism for a sound reproducing machine having a turn-table brake, a releasable brake carrying member, means to enforce after release both a swinging movement and a longitudinal brake applying movement thereof, and a spring tending to move said member toward a brake applying position.

80

7. An automatic stop mechanism for a sound reproducing machine having stop devices, including a contact arm, a brake carrying member connected therewith and movable as a unit, a spring tending to move said member toward a brake applying position, and means to cause said member after release to have both a turning and advancing movement.

85

8. An automatic stop mechanism for a sound reproducing machine having a turn-table brake, a brake carrying member normally restrained against brake-applying movement and having two movements including a brake-applying movement and a releasing movement, means to impart a releasing movement to said member through movement of the tone arm and a spring tending to move said member toward a brake-applying position, the releasing movement of said member being greater than the brake applying movement.

90

9. An automatic stop mechanism having a turn-table brake, a brake carrying member having a turning movement and a longitudinal brake-applying movement, means to hold the brake applying member retracted, and means to set it in motion by engagement with a tone arm part to turn the brake applying member and impart thereto a brake-applying movement, said means including guiding devices to cause said member both to turn and advance after being released.

100

10. An automatic stop mechanism for a sound reproducing machine having a stop device and controlling means therefor, including a rock shaft, a contact carrying arm associated therewith, a contact piece adjustably mounted thereon and devices to permit said contact carrying arm to be releasably held in fixed position with said rock shaft longitudinally retracted.

110

11. An automatic stop mechanism for a sound reproducing machine having a stop device and controlling means therefor, in-

120

125

130

- 4
- cluding a rock shaft, a contact carrying arm, a contact piece adjustably mounted thereon and a slotted guiding member controlling the position of said arm and adapted to permit it to be releasably set in fixed position. 5
12. An automatic stop mechanism for a sound reproducing machine, including a turn-table brake and means for controlling 10 the same comprising a rock shaft having its end formed to present a contact carrying arm, and means to releasably set said arm in fixed position including a guide which provides for both a longitudinal and a turning 15 movement of the rock shaft when said arm is released.
13. An automatic stop mechanism for a sound reproducing machine having a stop device, with means for controlling the same, 20 including a rock shaft, an arm secured thereto, a spring to move said arm and shaft longitudinally, means to hold said arm in a fixed position, and a guide to enforce both longitudinal and a turning movement of the 25 arm and rock shaft when the arm is released.
14. An automatic stop mechanism for a sound reproducing machine having a brake member, a rock shaft on the end of which 30 said brake member is carried, an arm secured to said rock shaft, a contact piece adjustably mounted thereon, a spring tending to move said rock shaft toward a brake- 35 applying position, means to hold said arm and rock shaft retracted, and means to cause retraction of the same when said arm is swung to a setting position, the latter being releasable by engagement with a tone arm part. 40
15. An automatic stop mechanism for a sound reproducing machine having a mov- able stop member having an adjustable contact piece adapted to be engaged by the tone arm part, said contact piece having a tapered bearing seat in said movable member. 45
16. An automatic stop mechanism for phonographs having a turn-table brake, a rock shaft for applying the brake, an upright member connected to the rock shaft, a contact part adjustably mounted on 50 said upright member adapted to be engaged by the tone arm, and means to hold said member set in position to be engaged by the tone arm but to cause instant movement thereof when said contact part is so engaged, 55 said means including a spring, the pressure of which is utilized to hold said member set but to move the same when the contact piece is engaged by the tone arm.
17. An automatic stop mechanism for 60 phonographs having a turn-table brake, a rock shaft for applying the brake, an upright member connected to the rock shaft, a contact part adjustably mounted on said upright member adapted to be engaged by the tone arm, and means to hold said member set in position to be engaged by the tone arm but to cause instant movement thereof when said contact part is so engaged. 65
18. An automatic stop mechanism for 70 phonographs having a turn-table brake, a rock shaft for applying the brake, an upright member connected to turn the rock shaft, a contact part adjustably mounted on said upright member adapted to be engaged by the tone arm, and a normally restrained 75 spring, releasable through tone-arm movement, to move the rock shaft.

In testimony whereof, I have signed my name to this specification.

ARTHUR G. ATWELL. [L. s.]
